CLAIM

The ornamental design for a footwear, as shown and described.

DESCRIPTION

FIG. 1 is a top, rear and right side perspective view of a footwear, showing my new design;

FIG. 2 is a bottom, front and right side perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The dotted broken lines in the drawings illustrate stitches of the footwear which form no part of the claimed design.
